UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL DISTRIBUTING MECHANISM.

Application filed August 2, 1923. Serial No. 655,166.

To all whom it may concern:

Be it known that I, ALFRED W. F. GUEST, a citizen of the United States, residing at Brooklyn, in the county of Kings and State 5 of New York, have invented certain new and useful Improvements in Typographical Distributing Mechanism, of which the following is a specification, reference being had therein to the accompanying drawing.

This invention relates to typographical machines, and more particularly to linotype machines of that class wherein the matrices, after casting, are presented to a primary distributor, which sorts them according to 10 font, and are thereafter delivered to one or another of a plurality of main distributors, which separate them according to character. These main character-distributors ordinarily each comprise a longitudinally ribbed or 15 permuted bar, a set of matrix conveying screws, and a so-called distributor box, which latter is equipped with separator dogs acting to permit the matrices to pass by 20 gravity, one at a time, into engagement with the conveying screws for transportation 25 along the bar. Heretofore, considerable difficulty has been experienced in handling the larger or display matrices which, due to their extreme thickness, frequently fail 30 to enter the grooves of the distributor screws in time to clear the separator dogs and thus become clogged in the distributor box, interrupting the distribution and oftentimes causing damage to the parts. This difficulty is 35 particularly pronounced in the case of the half-inch pitch distributor screw now in general use and which has a thread considerably wider than its groove. In attempting 40 to overcome the difficulty, such screw has sometimes been made with a reduced pitch (e. g., a quarter-inch pitch) at its receiving end, so that its thread will be more nearly vertical at that portion engaged by a matrix when released by the separator dogs. A 45 screw, as thus formed, affords some additional room for the released matrix but presents the drawback that the next or succeeding matrix, if also of the thicker variety, will be arrested by contact with the preceding matrix and thus interfere with the

separator dogs, giving rise to the objections before alluded to.

The present invention is intended to obviate the foregoing and other objections, and aims to adapt the distributor box to handle 55 matrices of all sizes without interference or delay. To this end, it is proposed to recess or cut away the threads of the distributor screws at points adjacent their groove entrances in such manner as to attain the desired result. The exact form and construction of the parts will best be understood 60 from the detailed description to follow.

In the accompanying drawings:

Fig. 1 is a side elevation, partly broken 65 away, of a portion of one of the main distributors of a linotype machine of the class stated;

Fig. 2 is an end elevation of the distributor box detached; and

Fig. 3 is an enlarged perspective view 70 showing one end of the improved distributor screw.

As shown, the distributor comprises the longitudinally ribbed or permuted bar A, 75 the set of rotary matrix conveying screws B (three in number), and the distributor box C. These parts are of well-known construction, although the conveying screws B are of the peculiar form disclosed in the Rogers 80 Patent No. 1,137,024, each having a half-inch pitch and a thread considerably wider than its groove, all for the purposes therein set forth. As is well understood in the art, the matrices X are fed to the conveying 85 screws, one at a time, under the control of the two vertically reciprocating separator dogs C¹ operated in synchronism with the screws and adapted to cooperate with notches X¹ formed in the lower ends of the 90 matrices. When a matrix is released by the dogs C¹, it slides downwardly along the distributor box rails C² until its projecting ears X² become engaged with the threads of the three conveying screws B, in which position the ears will enter the grooves of the screws as the latter rotate. In this way, the individual matrices are picked up by the screws and carried along the rails C² onto the distributor bar A, along which they 95 100

are propelled by the screws until released at the proper point. For further details as to the construction and mode of operation of the foregoing parts, reference may be had 5 to the Southwell Patent No. 792,472.

The present invention, in meeting the difficulties before mentioned, is designed to provide ample room for matrices of all sizes as they are released by the separator dogs 10 and to ensure a positive engagement between the conveying screws and the released matrices, as well as a quick advance of the latter from the distributor box. To this end, the conveying screws have their threads 15 cut away or recessed at the points where they are engaged by the released matrices, in such manner and to such extent that they will stand clear of the separator dogs and in position to be picked up and carried away 20 by the screws with the required celerity. In the present instance, and by way of example, the thread of each screw is cut away or recessed throughout a portion of its first convolution, as at B¹, preferably in a plane 25 at right angles to the screw axis, and then continued in its reduced form and at its original pitch to its extreme end. Reference is made particularly to Fig. 3, which shows one of the conveying screws on an 30 enlarged scale, the dotted lines indicating that portion of the thread cut away. It is pointed out that the recess B¹ is formed in the following side face of the screw-thread, as distinguished from its leading side face, 35 which is intact or uninterrupted throughout. As a result, when a thick matrix is released by the separator dogs, it will be allowed to slide forwardly into the recesses B¹ until arrested by the contact of the ears 40 X² with the vertical side faces of the reduced threads, as clearly indicated by the full-line showing in Fig. 1. By way of comparison, attention is drawn to the dotted-line showing in Fig. 1, which indicates the 45 position of the thick matrix at the time of its arrest by the old unrecessed form of screw. It will be seen, therefore, that in the use of the improved conveying screws, ample room is afforded for matrices of all 50 sizes without disturbing the effective pitch of the screws, which is uniform throughout. Moreover, due to the location of the recesses at or near the receiving ends of the screws, the latter are enabled to pick up 55 the matrices the instant they are released and carry them out of the way of the following matrices. These and other advantages will be apparent to those skilled in the art.

60 In the accompanying drawings, the invention has been shown only in preferred form and by way of example, and as applied to a linotype machine of the class stated, but obviously many alterations and modifications therein, and in its mode of application,

may be made without departing from the scope of the invention. It will be understood, therefore, that the invention is not limited to any specific form or embodiment, except in so far as such limitations are 70 specified in the claims.

Having thus described my invention, its construction and mode of operation, what I claim and desire to secure by Letters Patent of the United States, is as follows:

1. In or for a typographical distributing mechanism, a conveying screw having a thread of lesser width throughout its first convolution than that of its remaining portion.

2. In or for a typographical distributing mechanism, a conveying screw having its thread of greater width than that of its groove, the said thread being narrower throughout its first convolution than at its remaining portion.

3. In or for a typographical distributing mechanism, a conveying screw having its thread of greater width than that of its groove, the thread being cut away in its following side face from a point adjacent the entrance to said groove.

4. In or for a typographical distributing mechanism, a conveying screw having a thread whose following side face is disposed at right angles to the axis of the screw for a portion of its first convolution.

5. In or for a typographical distributing mechanism, a conveying screw having its thread of greater width than that of its groove, the thread being cut away in its following side face from a point adjacent the entrance to the groove and at right angles to the axis of said screw for a portion of its first convolution.

6. In or for a typographical distributing mechanism, a conveying screw having a thread of uniform pitch throughout and cut away in its following side face at a point adjacent its receiving end.

7. A typographical distributing mechanism including, in combination, a set of matrix conveying screws, a distributor box through which the matrices pass by gravity into engagement with said screws, and a pair of reciprocating dogs acting in synchronism with said screws for controlling the passage of the matrices through the distributor box, the said screws having their threads cut away or recessed at the points of engagement with the matrices, substantially as and for the purpose described.

8. A typographical distributing mechanism, including, in combination, a set of matrix conveying screws, and a distributor box through which the matrices pass by gravity into engagement with the screws, the said screws having their threads cut away or recessed at the points of engagement with the matrices.

9. A typographical distributing mechanism, including, in combination, a set of matrix conveying screws, a distributor box through which the matrices pass by gravity 5 into engagement with the screws, and an escapement acting in synchronism with said screws for controlling the passage of matrices through the distributor box, the said screws having their threads cut away or recessed at the points of engagement with the 10 matrices.

In testimony whereof, I have affixed my signature hereto.

ALFRED W. F. GUEST.
